(57) **CLAIM**

The ornamental design for portions of a container, as shown and described.

DESCRIPTION

FIG. 1 is a perspective view of portions of a container showing our new design;

FIG. 2 is a front elevational view thereof;

FIG. 3 is a rear elevational view thereof;

FIG. 4 is a side elevational view thereof;

FIG. 5 is an opposite side elevational view thereof; and,

FIG. 6 is a top plan view thereof; and the bottom view forms no part of the claimed invention.

The broken line showing of portions of a container is included for the purpose of illustrating only and forms no part of the claimed design.

1 Claim, 6 Drawing Sheets
